UNITED STATES PATENT OFFICE.

MARCUS M. LOCKARD, OF MERIDIAN, MISSISSIPPI.

CANNING APPARATUS.

1,253,843.

Specification of Letters Patent. Patented Jan. 15, 1918.

Application filed August 20, 1917. Serial No. 187,215.

To all whom it may concern:

Be it known that I, MARCUS M. LOCKARD, a citizen of the United States, residing at Meridian, in the county of Lauderdale, State of Mississippi, have invented certain new and useful Improvements in Canning Apparatus; and I do hereby declare the following to be a full, clear, and exact description of the invention, such as will enable others skilled in the art to which it appertains to make and use the same.

This invention relates to canning apparatuses.

The object of the invention is to provide a practical household canning apparatus in which fruit or vegetables may be preserved in cans or jars.

A further object of the invention is to provide a canning apparatus in which successive steps in the canning process can be simultaneously and continuously carried out.

With the above objects in view, and such others relating to the details of construction, as may hereinafter appear, my invention will now be fully set forth and described, reference being had to the accompanying drawings.

In the drawings:—

Figure 1 is a side elevation of the apparatus,

Fig. 2 is an end view thereof,

Fig. 3 is a transverse section,

Fig. 4 is a section on line 4—4 of Fig. 3,

Fig. 5 is a section on line 5—5 of Fig. 3, and

Fig. 6 is a perspective view of one of the can supports.

Referring more particularly to the drawings, 1 represents the vat or cooking receptacle which is built with a longitudinal fire box 2, the latter being closed at one end by means of a draft door 3 and terminating at the other end in a smoke box 4 from which the stack 5 rises. The arched fire box 2 forms, in a general way, within the vat, the side compartments 6, and above the fire box is built a secondary vat 7 within which an individual body of water may be heated, the bottom of the secondary vat 7 having a heating surface along its bottom in direct contact with the interior of the fire box 2. Within the secondary vat 7, which will be hereinafter called the scalding vat, there is suspended a tray or basket 8, which is constructed with sheet metal walls and a reticu-

lated bottom 9. Preferably, the bottom 9 is formed of heavy galvanized iron wire fabric. Each of the compartments 6 is intended to receive a frame 11 built up of four metallic corner posts 12, which at their lower ends are rigidly secured to a tray 13. At intermediate points, the transversely alined posts are connected by means of cross bars 14, and at their upper extremities are transversely connected by means of rods 15 upon which wooden handles 16 are mounted. The horizontal dimensions of the frame are such that it will practically fill one of the compartments 6, and in order to properly suspend the frame within a compartment and at the same time to provide a cover for the compartment which will be removable with the frame, I mount upon the posts 12 a cover plate 17 through which the posts project, the cover plate over reaching the outside dimensions of the frame, so that when the latter is inserted in the compartments 6, the cover will rest upon the upper edges of the vat. Aside from acting as additional braces for the frame the cross rods 14 act as supports for removable trays 18, which are brought into use, when produce is being put up in short glass jars or tin cans, but which are removed when tall cans are placed in the lower pan 13.

As above stated, the cover plate 17 is rigidly secured to the posts 12 so that it may act as a support for suspending the frame within its compartment. In order to suitably connect the cover plate 17 to the posts 12, the angle brackets 19 are connected to both the cover plate and the posts, these brackets not only properly and rigidly holding the plate in position, but further strengthening the frame structure.

In the use of the apparatus which has been described, the frames 11 are employed to support cans during the boiling or cooking process, and may be simultaneously or alternately employed as desired. The vat 7 is used for preliminary steps in the canning process, the basket 8 being used to support cans or jars for the exhausting process or being used to hold tomatoes or other produce for scalding in the water which is heated in the vat 7.

It will be apparent from the foregoing description that I have provided a very simple and practical canning apparatus, wherein several processes or steps in canning

operations may be simultaneously carried out. The apparatus draws largely for its quality of efficiency upon the fact that the number of operations may be simultaneously carried out by the use of a single fire.

What I claim as my invention is:

1. A canning apparatus, comprising in combination, a vat having a central fire box, said fire box subdividing the vat into compartments, a secondary vat mounted within the main vat and having a heating surface overlying the fire box, a scalding basket mounted in the secondary vat, and frames removably suspended in the compartments of the main vat.
2. A canning apparatus, comprising in combination, a vat having a central fire box, said fire box subdividing the vat into compartments, a secondary vat mounted within the main vat and having a heating surface overlying the fire box, a scalding basket mounted in the secondary vat, frames removably suspended in the compartments of the main vat, and cover plates for the compartments, said cover plates being carried by

the frames as integral parts thereof and overlying the edges of the compartments to suspend the frames thereby.

3. A canning apparatus, comprising in combination, a vat having a central fire-box, said fire box subdividing the vat into compartments, frames removably suspended in the compartments and cover plates for the latter, said cover plates being carried by the frames and overlying the edges of the compartments to suspend the frames thereby.

4. A canning apparatus, comprising in combination, a vat having a central fire-box, said fire box subdividing the vat into compartments, frames removably suspended in the compartments and cover plates for the latter, said cover plates being carried by the frames and closing the compartments when the frames are suspended therein.

In testimony whereof, I affix my signature 45
in the presence of two witnesses.

MARCUS M. LOCKARD.
